U.S. Appl. No. 29/478,811, filed Jan. 8, 2014; First Named Inventor: Albert W. Gebhard.

Primary Examiner — Clare E Heflin

(74) Attorney, Agent, or Firm — Margaret Polson; Polson Intellectual Property Law, PC

(57) **CLAIM**

The ornamental design for an LED work light, as shown and described.

DESCRIPTION

FIG. 1 is a front perspective view of our new design for an LED work light.

FIG. 2 is a front elevation view of FIG. 1.

FIG. 3 is a back elevation view of FIG. 1.

FIG. 4 is a top plan view of FIG. 1.

FIG. 5 is a bottom plan view of FIG. 1.

FIG. 6 is a right side elevation view of FIG. 1; and,

FIG. 7 is a left side elevation view of FIG. 1.

The mounting bracket, back cover and lenses are shown in broken lines and are for illustrative purpose only and form no part of the claimed design.

1 Claim, 4 Drawing Sheets
